UNITED STATES PATENT OFFICE.

EUGENE CLAYBORNE ROBINSON, OF DOUGLAS, ARIZONA, ASSIGNOR OF FIFTY-FIVE ONE-HUNDREDTHS TO PHELPS DODGE CORPORATION, A CORPORATION OF NEW YORK.

RABBLE.

1,353,422.

Specification of Letters Patent. Patented Sept. 21, 1920.

Application filed January 17, 1919. Serial No. 271,746.

To all whom it may concern:

Be it known that I, EUGENE CLAYBORNE ROBINSON, citizen of the United States, residing at Douglas, in the county of Cochise 5 and State of Arizona, have invented certain new and useful Improvements in Rabbles, of which the following is a specification.

This invention relates to improvements 10 in rabbles for metallurgical roasting ovens of the type in which the rabble arms are cooled by air.

As is well known, rabbles in this type of furnace ordinarily embody an inner hollow shaft and an outer inclosing shaft, the arm 15 of the rabble comprising an outer member and an inner member through which latter air is supplied and passes into the outer member of the arm and is thence conducted to the outer shaft of the rabble through 20 which it passes to the air outlets. In one type of rabble the inner end of the inner member of the rabble arm is secured in an opening in the inner or cooling-fluid supply shaft of the rabble, and the inner end of 25 the outer member of the arm is secured in an opening in the outer or exhaust-fluid conducting shaft of the rabble, the said members of the arm opening directly into the interiors of the respective shafts. For 30 the purpose of securely supporting the outer member of the arm to enable it to withstand the stresses to which the arm is subjected as it operates against ore to be roasted upon the hearths of the furnace, it 35 has been customary to seat the inner end of the outer member of the rabble arm in a boss located at and surrounding the opening in the outer shaft of the rabble. This arrangement, however, presents disadvan- 40 tages for if the boss is made sufficiently long to provide a firm and secure seat for the inner end of the outer member of the rabble arm, it is insufficiently cooled in the operation of the roaster, and as a consequence 45 soon becomes burned away. If, on the other hand, in order to prevent burning away, the boss is formed relatively short, the said outer member of the rabble arm will not have sufficient purchase in the socket pro- 50 vided by the boss to withstand the stresses to which it is subjected. The primary object of the present invention is, therefore, to provide means for so seating the rabble

arm in the rabble shaft that a bearing of maximum length will be afforded the arm 55 and at the same time a boss of minimum length only need be provided upon the outer shaft of the rabble.

The figure of the accompanying drawing is a view partly in vertical section and 60 partly in elevation of a portion of a roaster rabble embodying the present invention.

In the drawing the numeral 1 indicates the inner or cooling-fluid supply shaft of the rabble and the numeral 2 indicates the 65 outer or exhaust-fluid-conducting shaft of the rabble, these shafts being concentrically positioned with relation to each other, and the shaft 1 being connected with any suitable source of air supply such, for example, 70 as a blast fan, and the shaft 2 being in communication with the usual outlets for the air after it has performed its function of cooling the rabble arms. For a purpose to be presently explained, the shaft 1 is formed 75 at intervals with openings 3 through which the cooling air is to be discharged into the rabble arms, and surrounding each opening the shaft is formed exteriorly with a flange 4 which forms a seat, indicated by the num- 80 eral 5, the flange being concentric to the respective opening 3 and the seat being of greater diameter than the said opening so that a seating shoulder 6 is provided at the inner end of the said seat. Opposite each 85 opening 3 in the shaft 1, the shaft 2 is formed with an opening 7 and exteriorly with an integral collar or boss 8 which is sufficiently short to guard against undue heating of its outer portion, which is the 90 disadvantage heretofore pointed out for the ordinary forms of rabbles in which this boss has been formed of considerable length in order to provide a sufficiently long bearing for the inner end of the rabble arm. In- 95 teriorly the boss is of the same diameter as the opening 7 and it is preferable that the boss be interiorly flared at its outer end as indicated by the numeral 9, so as to permit of the more ready insertion of the rab- 100 ble arm when fitting the arm into place. Also, for a purpose to be presently pointed out, each boss 8 is formed in its upper side with an opening 10.

The rabble arm is indicated in general by 105 the numeral 11 and the same comprises an

outer tubular member 12 and an inner tubular member 13, the outer member 12 being closed at its outer end by a plug 14 having the usual apertured lug 15 to receive the usual 5 pin (not shown) which is to hold in place upon the arm the rakes of the rabble. It is preferable that the plug 14 be formed concave in its inner side as indicated by the numeral 16 so that the cooling air currents 10 issuing from the outer end of the tube or member 13 will be deflected and turned back, as indicated by the arrows in the drawing, without any back pressure in the said tube 13.

15 The rabble arm embodying the present invention differs materially from the ordinary rabble arm inasmuch as in its construction the inner end of the inner tube is connected or united to the inner end of the outer tube 20 or member and the said inner tube or member is supported entirely by the said outer member, whereas in the ordinary construction, as before stated, the inner end of the inner tube or member is secured in the opening in the inner shaft of the rabble and likewise the inner end of the outer tube or member is secured in the opening or boss provided for its reception upon the outer shaft of the rabble. Thus in the present construction 25 the said inner end of the inner tube or member 13 is secured, as indicated by the numeral 17, within the opening of a bushing 18 which bushing in turn is fitted and secured within the inner end of the outer tube 30 or member 12, these parts being permanently and rigidly united so as to constitute practically an integral structure. The arrangement is such that the inner ends of the members 12 and 13 and the exposed face of the 35 bushing all touch or occupy a common plane or, in other words, are flush with respect to one another.

In assembling the rabble arm with the rabble shaft as a whole, the inner end of the 40 arm is fitted through the boss 8 and opening 7 and into the seat 5 and snugly fitting within the opening and seat, as clearly shown in the drawing and resting against the seating shoulder 6. Interiorly the inner member or tube 13 of the arm is of substantially the same diameter as the opening 3 so that there will be an unobstructed passage of the air or other cooling fluid from the shaft 1 into the said member or tube 13. 45 The cooling fluid after passing through the member 13, issues from the outer end of the said member, which end is located relatively close to the concave inner side of the plug 14, and is deflected so as to flow in an inward direction through the outer tube or member 12, finally issuing through openings 19 formed in the said member at the inner end thereof, these openings 19 being so located as to communicate with the space between the inner and outer shafts 1 and 2. 50

After issuing from the openings 19 into the space between the shafts 1 and 2, the cooling fluid will of course pass to other arms and will finally exhaust through the usual openings provided for this purpose. A pin 70 55 75 70 is to be fitted through the opening 10 and through an opening 21 in the outer member or tube 12 of the rabble arm and this pin serves to prevent outward displacement of the arm with relation to the shaft. 75

From the foregoing description of the invention it will be evident that both members of the rabble arm are so connected together that the arm constitutes substantially an integral whole. 80

As before pointed out, the distinctive advantage gained by the construction forming the subject matter of the present invention is that the inner end of the arm as a whole is given a bearing of maximum length in the rabble shaft, although the boss 8 may be in itself very short. As a result the rabble arm is enabled to better resist the stresses to which it is subjected in operating upon the ore distributed upon the hearths of the furnace and there is little or no likelihood of the bosses 8 being burned out. Furthermore, the arm as a whole may be readily and quickly fitted into place and thus the necessity of first securing the inner end of the inner tube or member 13 in place in the usual opening in the inner shaft 1 and subsequently independently fitting or securing the inner end of the outer tube or member 12 in the boss upon the shaft 2, is wholly obviated and this of course means a considerable saving in time and labor aside from obviating the other disadvantages heretofore pointed out attending the use of the old construction. 95 100 105

Having thus described the invention, what is claimed as new is:

1. In apparatus of the class described, a cooling-fluid supply shaft, an inclosing exhaust-fluid conducting shaft, the first mentioned shaft having a seat and an opening surrounded thereby and in communication with its interior and the second mentioned shaft having an opening opposite the seat, and a rabble arm comprising inner and outer tubular members, the inner member being supported within and by the outer member and the inner end of the outer member of the arm being fitted through the said opening in the second-mentioned shaft and into the said seat. 110 115 120

2. In apparatus of the class described, a cooling-fluid supply shaft provided exteriorly with a seat and with an opening surrounded thereby, an inclosing exhaust-fluid conducting shaft having an opening opposite the seat, and a rabble arm including an outer tubular member fitted at its inner end through the opening in the exhaust-fluid conducting shaft and into the seat and an 125 130

inner tubular member in communication with the cooling-fluid supply shaft and with the interior of the outer member.

3. In apparatus of the class described, a cooling-fluid supply shaft, an inclosing fluid conducting shaft, the first mentioned shaft having a seat and an opening surrounded thereby in communication with its interior and the second mentioned shaft having an opening opposite the seat, and a rabble arm comprising inner and outer tubular members substantially integrally connected at their inner ends, the arm being fitted at its inner end through the opening in the second-mentioned shaft and into the seat and the said inner tubular member communicating with the interior of the cooling-fluid supply shaft.

4. In apparatus of the class described, a cooling-fluid supply shaft, an inclosing exhaust-fluid conducting shaft, the shafts having alined openings and the first mentioned shaft having a seat surrounding its respective opening and disconnected from the exhaust-fluid conducting shaft, and a rabble arm including an outer tubular member and an inner tubular member, the outer tubular member of the arm being fitted through the opening in the exhaust-fluid conducting shaft and engaging in the said seat in the cooling-fluid conducting shaft and the said inner tubular member at its inner end communicating with the interior of the cooling-fluid supply shaft through the opening in said shaft.

5. In apparatus of the class described, an inner cooling-fluid supply shaft, an inclosing exhaust-fluid conducting shaft, the supply shaft having an opening and being provided exteriorly surrounding its opening with a seat, the exhaust-fluid conducting shaft having an opening opposite the opening in the first mentioned shaft, and a rabble arm including an outer tubular member, an inner tubular member, and a bushing secured within the inner end of the outer

member and within the opening of which the inner end of the inner member is secured, whereby to connect the said members and afford a support for the inner member, the outer member having an outlet opening and the outer end of the inner member communicating with the interior of the outer member, the said outer member of the arm being fitted at its inner end through the opening in the exhaust-fluid conducting shaft and into the seat upon the cooling-fluid supply shaft with its said opening communicating with the space between the shafts, the inner end of the inner member communicating with the interior of the cooling-fluid supply shaft through the said opening therein.

6. A rabble arm comprising an outer tubular member and an inner tubular member located within and spaced from the wall of the outer tubular member, and means at the inner end of the arm connecting the said members and constituting the sole support for the inner member.

7. In apparatus of the class described, an inner cooling-fluid supply shaft, an inclosing exhaust-fluid conducting shaft, the shafts having oppositely located openings and the first mentioned shaft being provided exteriorly with a seat surrounding its opening and free from connection with the second mentioned shaft, and a rabble arm comprising inner and outer tubular members, the outer member being connected with the inner member at the inner end of the arm and bodily supported thereby, the said outer member of the arm being fitted through the opening in the second mentioned shaft and seating at its inner end in the seat in the first mentioned shaft in position with the inner end of the inner tubular member of the arm communicating with the opening in the first mentioned shaft.

In testimony whereof I affix my signature.

EUGENE CLAYBORNE ROBINSON. [L. S.]
